UNITED STATES PATENT OFFICE.

CHARLES E. STELLER, OF MILWAUKEE, WISCONSIN.

KNOB ATTACHMENT.

SPECIFICATION forming part of Letters Patent No. 349,011, dated September 14, 1886.

Application filed July 19, 1886. Serial No. 208,429. (No model.)

To all whom it may concern:

Be it known that I, CHARLES E. STELLER, of Milwaukee, in the county of Milwaukee and State of Wisconsin, have invented new and 5 useful Improvements in Door-Knob Attachments; and I do hereby declare the following to be a full, clear, and exact description of said invention, reference being had to the accompanying drawings, and to the letters or figures 10 of reference marked thereon, which form a part of this specification.

The object of my invention is to provide a door-knob attachment that is simple in form and inexpensive of construction, that can 15 readily be attached to doors of different thicknesses, and is adapted to be used in connection with any of the many forms of door-locks in which a spindle is used.

In the drawings, Figure 1 is a rear view of 20 a device embodying my invention. Fig. 2 is a central vertical section of the same device at right angles to the position shown in Fig. 1. Figs. 3, 4, 5, and 6 are details of the same device.

25 The same letters refer to like parts in all the views.

A is an escutcheon, adapted to be attached to a door by screws through the apertures *m m*, or otherwise. The escutcheon is provided 30 with a chambered rose, B, adapted to receive and support the shank of the knob and its bearings.

C is the shank, which terminates at its outer end in the disk D, integral therewith.

35 E is the shell of the knob, which is provided on the inside of its walls with two or more stops or bearings, *n o*. The disk D is adapted to enter and fit into the shell E at its open side and rest against the outer ends of 40 the stops *n o*, and the disk is affixed to the shell by screws *p*, passing through apertures in the disk and turning into screw-threaded apertures in the stops *n n*. The shank C is provided with an annular groove, *q*, which is 45 adapted to receive the inwardly-projecting flanges *r r* of the semicircular sleeves or boxes F F. The two semicircular boxes F F are adapted to fit upon and surround the inner end of the shank C, and to enter and fit in the 50 chamber of the rose B. The inwardly-projecting flanges *r r* are adapted to enter the groove *q*, while the outsides of the ends of the

boxes F F bear against the inside of the outer end wall or shoulder, *s*, of the rose B, whereby the shank is kept from being withdrawn from 55 the rose. An outwardly-projecting lug, *t*, on the inner end of each of the boxes F is let into a recess in the inner side of the rose or escutcheon, which lug is adapted to restrain the boxes from rotating or moving around in 60 their bearings when the shank is rotated, and this lug will also retain the shank C against its being withdrawn from the rose when the boxes F F are in position around it in the rose, and may be adapted to restrain the boxes 65 from contact with the end wall or shoulder, *s*, if desired.

Instead of the two boxes F F, one semicircular box or one or more keys, G G', either with or without the lug *t*, as shown at G and 7c G', respectively, may be used to retain the shank in the escutcheon, and when one box or one or more keys are used the walls of the chamber of the rose and escutcheon are made to fit closely about the shank, as shown in 75 Fig. 3, a sufficient recess being provided for the box or key. That part of the shank C from the groove *q* to the inner end is a little shorter than the boxes F F, and thereby the end of the shank is prevented from bearing 80 against the door. The spindle H is a plain simple four-square or angular iron rod without screw-holes, pins, or lugs, adapted to enter the aperture in the shank in the usual manner. This spindle not being in any way 85 affixed to the shank, my knob attachment can be used with doors of any thickness.

It will be seen that to attach the knob to a door the shank C is first thrust into and through the rose and escutcheon up to the 90 knob, or so far that the groove *q* is beyond the escutcheon. The boxes F F (or key G) are then placed on the shank with the flanges *r r* in the groove *q*. The shank C is then drawn out to position as shown in Fig. 2, and the escutcheon is affixed to the door by screws through the apertures *m m*. The knob being so attached to the door cannot be withdrawn in any part of its rotary movement, and the shank having a close-fitting bearing in the 100 boxes or keys, which also enter the groove in the shank, any wobbling is prevented. The parts of the device hereinbefore described which are new and which embody my inven-

tion may not only be used with the shell-knob, as hereinbefore described, but with knobs constructed of other forms and material, and I do not wish to limit my invention in any way by the form or construction of the knob.

What I claim as new, and desire to secure by Letters Patent, is—

1. In door-knob attachments, a knob-shank provided with a groove about it, in combination with an escutcheon provided with a chambered rose having an outer wall or shoulder, *s*, and one or more retaining boxes or keys, each provided with an inwardly-projecting flange, *r*, substantially as described.

2. In door-knob attachments, a knob-shank, *s*, provided with a groove, *q*, about it, in combination with a box or key provided with an inwardly-projecting flange, *r*, and an outwardly-projecting lug, *t*, and an escutcheon provided with a chambered rose for the reception of the box or key and a recess for the lug *t*, substantially as described.

In testimony whereof I affix my signature in presence of two witnesses.

CHARLES E. STELLER.
